CARTON

Robert Van Rosen, New York, N. Y., assignor to
 J. Makowsky Corporation, a corporation of New
 York

Application June 12, 1944, Serial No. 539,903

11 Claims. (Cl. 229—16)

The invention relates to cartons used for various goods. Preferably the carton will be made of some such material as cardboard or the like, which comes in sheet form. A blank will be cut from the sheet and then bent and folded into proper form to make the carton or receptacle.

The invention contemplates a neat looking, relatively sturdy carton which may be especially useful as a container for jars and the like of cosmetics although it may be used for any material.

In the accompanying drawings showing a specific embodiment of the invention, Fig. 1 is a plan view of a blank from which the carton may be made. Fig. 2 is a top plan view of the completed carton with the cover open. Fig. 3 is a fragmentary vertical section on the line 3—3 of Fig. 2. Fig. 4 is a fragmentary vertical section on the line 4—4 of Fig. 2. Figs. 5, 6 and 7 are perspective views of the blank partially formed into the carton. Fig. 8 is a perspective view of a completed carton illustrating the last step in its formation. Fig. 9 is a perspective view of a carton showing an optional form of top. Fig. 10 is a perspective of another optional form of carton and top, and Fig. 11 is a fragmentary plan view of a part of the blank for formation of the top shown in Fig. 10. The figures are on different scales.

In Fig. 1 the blank from which the carton is to be formed is shown as a single sheet of material. The solid lines of the drawings show lines on which cuts are made. The dot-and-dash lines show lines on which folds are made and these may be scored or otherwise prepared for easy and accurate folding.

In forming the carton, the members 12, 17 at the edges of the members 11 and 16 and the members 25 and 26 at the sides of the member 27 may be turned up as illustrated in Fig. 5. Then, as shown in Fig. 6, the members 11 and 16 may be folded upward at right angles to the member 10 and the members 21 and 22 are folded inward and interlocked in any suitable manner as by the slot 23 in one side of member 21 engaging with the slot 24 in the opposite side of the member 22. The members 21 and 22 thus join to hold the side members in place and to form a back wall. Thus the member 10 becomes the outer front wall of the carton and the members 11 and 16 become the outer side walls of the carton. Now the members 33 and 34 at the ends of the member 35 may be bent up and inwardly to lie in contact with the surface of the member 35. Now the rectangular frame made up of

members 10, 11, 16, 21 and 22 may be turned up, causing the member 26 to engage and turn up the member 17 while the member 25 engages and turns up the member 12. The member 27 thus becomes the bottom of the carton. The member 35, with its inturned members 33 and 34, is turned upward to be against the interlocked members 21 and 22. Thus, as shown in Fig. 7, the member becomes the outer back wall of the carton. Members 36 and 37 are folded together as partially indicated in Fig. 6 and together they are folded downwardly against the inner side of the interlocked members 21 and 22 and between the outer side walls 11 and 16. This holds the top or cover 41 in position as shown in Fig. 7. To aid in manipulation and inserting the members 36 and 37 in place, one or both of the ends of either or both may be curved or beveled as indicated at 39 and 40. Now the members 13 and 18 are folded inwardly to form top side walls and the members 14 and 19 are folded downwardly, enveloping, respectively, the members 12 and 25 and the members 17 and 26, and forming inner side walls for the carton. Thus the members 12 and 25 form additional reinforcing for one side wall while the members 17 and 26 form additional reinforcing for the other side wall. The rear ends of the side walls 14 and 19 engage and hold in position the folded members 36 and 37. The members 15 and 20 are folded inwardly and lie against the bottom member 27 and form bracing members for the side walls. Then the member 28 is folded inwardly forming a front top wall and overlies the front ends of the top side walls 13 and 18. The ends of section 28 are beveled or inclined at 28a to give the appearance of a beveled joint as indicated in Fig. 2. Because of the beveled ends of 28 the section 29 is narrower than the section 10 by an amount equal to the width of the sections 13 and 18. The section 29 is now bent downwardly going between the inner side walls 14 and 19 and holding them in place. The section 30 is bent rearwardly and overlies the bracing members 15 and 20 and engages the catch 31 on the member 15 and the catch 32 on the member 20, thus holding the parts assembled and in place without the use of paste or any other fastening means than the parts of the blank itself. The section 41 may then be folded forward at right angles to the section 37 to form a cover for the carton. The section 42 may then be folded downwardly at right angles to the cover 41 and its end 43 may be locked by passing

through the slot 44 provided in the front wall 10.

The cover 41 is hinged to the member 37 and the member 37 is held in place by the ends of the inner wall members 14 and 19 so that the cover may be raised or opened without loosening the carton parts.

When an article is in the carton it may rest on the members 15, 20 and 30 and hold the walls in place and this condition may persist when the article is removed depending largely on the substance of which the carton is made or how well it retains the shape into which it is folded. However, in order to assure the carton being held in proper form the members 15 and 20 interlock 15 with the member 30 to hold the wall members in place.

The folded members 12, 17, 25 and 26 reinforce or strengthen the side walls and they also tend to produce an improved appearance to the device. Some or all of these members may be omitted but when present they present a neat and better finished appearance to the exposed edges of the members 11, 16 and 27 respectively. Likewise the folded members 33 and 34 reinforce or strengthen the back wall and they also tend to produce an improved appearance to the device. One or both of them may be omitted but when present they present a neat and better finished appearance to the exposed ends of the member 35. Because of the presence of the members 12, 17, 25, 26, 33 and 34 smooth doubled or curved edges show instead of the single cut edges which might otherwise be exposed.

Since they lie adjacent each other in the blank as shown in Fig. 1 the forward ends of the members 12 and 25, and 17 and 26 respectively are beveled. This beveling also may make easier their insertion between the outer and inner side wall members.

The top member 41 with or without the member 37 may be omitted and an uncovered carton used. The slot engagement of the member 43 may not be necessary. The slot 44 and the member 43 may be omitted or may be differently formed and the cover may be held in place by other suitable means or gravity may be sufficient to hold it in position.

As shown in Fig. 9, the cover member 41a may be shortened so that the narrow closing section 42a may rest between the side walls and against the inner side of the front wall. A cut-out thumb piece 45 may be provided, which rests on top of the front wall and limits the downward or inward movement of the top 41a and may also form a convenient means for pulling the top up and open.

As shown in Figs. 10 and 11, the top member 41b may be provided with a closing section 46 which may be bent downwardly. At about the bending line there may be provided a slot 48 through which may be passed an upwardly turned tab 47 extending from the member 46. Thus the top member 41b may be closed between the sides and front walls, with the member 46 resting against the front wall to hold the cover by friction. The tab 47 extends outwardly and may be grasped to pull the top of the carton up and open.

The sizes, proportions, shapes and specific arrangements of the various parts are not essential to the invention which may be embodied in a device incorporating various changes and omissions.

I claim as my invention:

1. In a carton formed from a single sheet of material, a front wall having a slot therein, side walls articulated at each end of the front wall, side top walls articulated at the tops of the side walls and extending inwardly, inner side walls articulated at the inner sides of the top side walls and extending downwardly, side wall brace members articulated at the lower edges of the inner side walls and extending inwardly and provided with catch members, a front top wall articulated at the top of the front wall and extending inwardly and provided with inwardly inclined ends and overlying the ends of the top side walls, an inner front wall articulated at the inner edge of the front top wall and extending downwardly between the front ends of the inner side walls, a front wall brace member articulated at the bottom of the inner front wall and extending inwardly overlying the side wall brace members and held by the catch members, reinforcing members articulated at the bottom edges of the side members having inclined front ends and extending upwardly between the inner and outer side wall members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member having inclined front edges and extending upwardly between the inner side wall members and the reinforcing members of the side wall members, a rear wall articulated at the rear edge of the bottom member and extending upwardly, reinforcing members articulated at the sides of the rear wall and extending inwardly in contact with the rear wall and substantially in contact with the rear side of the connecting members, a first reinforcing member articulated at the top edge of the rear wall and extending downwardly substantially in contact with the front side of the connecting members, a second reinforcing member articulated at the bottom edge of the first reinforcing member and extending upwardly substantially in contact therewith, both the last-mentioned reinforcing members having ends inclined upwardly and lying back of the rear ends of the inner side walls, a cover member articulated at the top edge of the second reinforcing member and extending forwardly, and a locking flap articulated to the front edge of the cover member and extending downwardly and engaging the slot in the front member.

2. In a carton formed from a single sheet of material, a front wall, side walls articulated at each end of the front wall, side top walls articulated at the tops of the side walls and extending inwardly, inner side walls articulated at the inner sides of the top side walls and extending downwardly, side wall brace members articulated at the lower edges of the inner side walls and extending inwardly and provided with catch members, a front top wall articulated at the top of the front wall and extending inwardly and provided with inwardly inclined ends and overlying the ends of the top side walls, an inner front wall articulated at the inner edge of the front top wall and extending downwardly between the front ends of the inner side walls, a front wall brace member articulated at the bottom of the inner front wall and extending inwardly overlying the side wall brace members and held by the catch

members, reinforcing members articulated at the bottom edges of the side members having inclined front ends and extending upwardly between the inner and outer side wall members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member having inclined front edges and extending upwardly between the inner side wall members and the reinforcing members of the side wall members, a rear wall articulated at the rear edge of the bottom member and extending upwardly, a first reinforcing member articulated at the top edge of the rear wall and extending downwardly substantially in contact with the front side of the connecting members, a second reinforcing member articulated at the bottom edge of the first reinforcing member and extending upwardly substantially in contact therewith, both the last-mentioned reinforcing members having ends inclined upwardly and lying back of the rear ends of the inner side walls, and a cover member articulated at the top edge of the second reinforcing member and extending forwardly.

3. In a carton formed from a single sheet of material, a front wall, side walls articulated at each end of the front wall, side top walls articulated at the tops of the side walls and extending inwardly, inner side walls articulated at the inner sides of the top side walls and extending downwardly, side wall brace members articulated at the lower edges of the inner side walls and extending inwardly and provided with catch members, a front top wall articulated at the top of the front wall and extending inwardly and provided with inwardly inclined ends and overlying the ends of the top side walls, an inner front wall articulated at the inner edge of the front top wall and extending downwardly between the front ends of the inner side walls, a front wall brace member articulated at the bottom of the inner front wall and extending inwardly overlying the side wall brace members and held by the catch members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member having inclined front edges and extending upwardly between the inner side wall members and the reinforcing members of the side wall members, a rear wall articulated at the rear edges of the bottom member and extending upwardly, a first reinforcing member articulated at the top edge of the rear wall and extending downwardly substantially in contact with the front side of the connecting members, a second reinforcing member articulated at the bottom edge of the first reinforcing member and extending upwardly substantially in contact therewith, both the last-mentioned reinforcing members having ends inclined upwardly and lying back of the rear ends of the inner side walls, and a cover member articulated at the top edge of the second reinforcing member and extending forwardly.

4. In a carton formed from a single sheet of material, a front wall, side walls articulated at

each end of the front wall, side top walls articulated at the tops of the side walls and extending inwardly, inner side walls articulated at the inner sides of the top side walls and extending downwardly, side wall brace members articulated at the lower edges of the inner side walls and extending inwardly and provided with catch members, a front top wall articulated at the top of the front wall and extending inwardly and provided with inwardly inclined ends and overlying the ends of the top side walls, an inner front wall articulated at the inner edge of the front top wall and extending downwardly between the front ends of the inner side walls, a front wall brace member articulated at the bottom of the inner front wall and extending inwardly overlying the side wall brace members and held by the catch members, connecting members articulated to the rear ends of the side walls and extending inwardly and interlocking with each other, a bottom member articulated at the bottom edge of the front wall and extending rearwardly to the rear ends of the side walls and in contact with the side wall brace members, a rear wall articulated at the rear edge of the bottom member and extending upwardly, a first reinforcing member articulated at the top edge of the rear wall and extending downwardly substantially in contact with the front side of the connecting members, a second reinforcing member articulated at the bottom edge of the first reinforcing member and extending upwardly substantially in contact therewith, both the last-mentioned reinforcing members having ends inclined upwardly and lying back of the rear ends of the inner side walls, and a cover member articulated at the top edge of the second reinforcing member and extending forwardly.

5. In a carton formed from a single sheet of material, a front wall, side walls articulated at each end of the front wall, inner side walls articulated at the tops of the side walls and extending downwardly, side wall brace members articulated at the lower edges of the inner sidewalls and extending inwardly and provided with catch members, an inner front wall articulated at the top of the front wall and extending downwardly between the front ends of the inner side walls, a front wall brace member articulated at the bottom of the inner front wall and extending inwardly overlying the side wall brace members and held by the catch members, reinforcing members articulated at the bottom edges of the side members extending upwardly between the inner and outer side wall members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member extending upwardly between the inner side wall members and the reinforcing members of the side wall members, a rear wall articulated at the rear edge of the bottom member and extending upwardly, reinforcing members articulated at the sides of the rear wall and extending inwardly in contact with the rear side of the connecting members, a first reinforcing member articulated at the top edge of the rear wall and extending downwardly substantially in contact with the front side of the connecting members, a second reinforcing member articu-

lated at the bottom edge of the first reinforcing member and extending upwardly substantially in contact therewith, both the last-mentioned reinforcing members having ends inclined upwardly and lying back of the rear ends of the inner side walls, and a cover member articulated at the top edges of the second reinforcing member and extending forwardly.

6. In a carton formed from a single sheet of material, a front wall, side walls articulated at each end of the front wall, inner side walls articulated at the tops of the side walls and extending downwardly, side wall brace members articulated at the lower edges of the inner side walls and extending inwardly and provided with catch members, an inner front wall articulated at the top of the front wall and extending downwardly between the front ends of the inner side walls, a front wall brace member articulated at the bottom of the inner front wall and extending inwardly overlying the side wall brace members and held by the catch members, reinforcing members articulated at the bottom edges of the side members extending upwardly between the inner and outer side wall members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member extending upwardly between the inner side wall members and the reinforcing members of the side wall members, a rear wall articulated at the rear edge of the bottom member and extending upwardly, reinforcing members articulated at the sides of the rear wall and extending inwardly in contact with the rear wall and substantially in contact with the rear side of the connecting members, and a reinforcing member articulated at the top edge of the rear wall and extending downwardly substantially in contact with the front side of the connecting members.

7. In a carton formed from a single sheet of material, a front wall, side walls articulated at each end of the front wall, inner side walls articulated at the tops of the side walls and extending downwardly, side wall brace members articulated at the lower edges of the inner side walls and extending inwardly, an inner front wall articulated at the top of the front wall and extending downwardly between the front ends of the inner side walls, a front wall brace member articulated at the bottom of the inner front wall and extending inwardly overlying the side wall brace members and interlocking therewith, reinforcing members articulated at the bottom edges of the side members extending upwardly between the inner and outer side wall members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member extending upwardly between the inner side wall members and the reinforcing members of the side wall members, a rear wall articulated at the rear edge of the bottom member and extending upwardly and substantially in contact with the rear side of the connecting members, a first reinforcing member articulated at the

top edge of the rear wall and extending downwardly substantially in contact with the front side of the connecting members, a second reinforcement.

5 forcing member articulated at the bottom edge
of the first reinforcing member and extending
upwardly substantially in contact therewith, both
the last-mentioned reinforcing members having
ends inclined upwardly and lying back of the rear
ends of the inner side walls, and a cover member
10 articulated at the top edge of the second reinforcing
member and extending forwardly.

8. In a carton formed from a single sheet of material, a front wall, side walls, a top flap, and a bottom flap, the top flaps are joined together by a fold line extending from the outer edge of the front wall to the outer edge of the side wall.

15 material, a front wall, side walls articulated at each end of the front wall, inner side walls articulated at the tops of the side walls and extending downwardly, side wall brace members articulated at the lower edges of the inner side walls and extending inwardly and provided with catch

20 members, an inner front wall articulated at the top of the front wall and extending downwardly between the front ends of the inner side walls, a front wall brace member articulated at the bottom of the inner front wall and extending inwardly overlying the side wall brace members and

held by the catch members, connecting members articulated to the rear ends of the side walls and extending inwardly and interlocking with each other, a bottom member articulated at the bottom edge of the front wall and extending rearwardly to the rear ends of the side walls and in-

36 contact with the side wall brace members, reinforcing members articulated at the sides of the bottom member extending upwardly between the side wall members, a rear wall articulated at the
35 rear edge of the bottom member and extending upwardly and substantially horizontally to the
36 top of the bottom member, a top wall articulated

45 articulated at the bottom edge of the first reinforcing member and extending upwardly substantially in contact therewith, both the last-mentioned reinforcing members having ends inclined upwardly and lying back of the rear ends of the inner side walls, and a cover member articulated at the top edge of the second reinforcing member and extending forwardly.

50 9. In a carton formed from a single sheet of material, a front wall, side walls articulated at each end of the front wall, inner side walls articulated at the tops of the side walls and extending downwardly, side wall brace members articulated
55 at the lower edges of the inner side walls

66 the lower edges of the inner side walls and
extending inwardly and provided with catch
members, an inner front wall articulated at the
top of the front wall and extending downwardly
between the front ends of the inner side walls, a
60 front wall brace member articulated at the bot-
tom of the inner front wall

ton of the inner front wall and extending inwardly overlying the side wall brace members and held by the catch members, connecting members articulated to the rear ends of the side walls and 65 extending inwardly and interlocking with each other, a bottom member articulated at the bot-

70 bottom edge of the front wall and extending rearwardly to the rear ends of the side walls and in contact with the side wall brace members, a rear wall articulated at the rear edge of the bottom member and extending upwardly and substantially in contact with the rear side of the connecting members, a first reinforcing member articulated at the top edge of the rear wall and 75 extending downwardly substantially in contact

with the front side of the connecting members, a second reinforcing member articulated at the bottom edge of the first reinforcing member and extending upwardly substantially in contact therewith, both the last-mentioned reinforcing members having ends inclined upwardly and lying back of the rear ends of the inner side walls, and a cover member articulated at the top edge of the second reinforcing member and extending forwardly.

10. In a carton formed from a single sheet of material, a front wall, side walls articulated at each end of the front wall, inner side walls articulated at the tops of the side walls and extending downwardly, side wall brace members articulated at the lower edges of the inner side walls and extending inwardly and provided with catch members, an inner front wall articulated at the top of the front wall and extending downwardly between the front ends of the inner side walls, a front wall brace member articulated at the bottom of the inner front wall and extending inwardly overlying the side wall brace members and held by the catch members, reinforcing members articulated at the bottom edges of the side members extending upwardly between the inner and outer side wall members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member extending upwardly between the inner side wall members and the reinforcing members of the side wall members, a rear wall articulated at the rear edge of the bottom member and extending upwardly, reinforcing members articulated at the sides of the rear wall and extending inwardly in contact with the rear wall and substantially in contact with the rear side of the connecting members, a first reinforcing member articulated at the top edge of the rear wall and extending downwardly substantially in contact with the front side of the connecting members, a second reinforcing member articulated at the bottom edge of the first reinforcing member and extending upwardly substantially in contact therewith, both the last-mentioned reinforcing members having ends inclined upwardly and lying back of the rear ends of the inner side walls, a cover member articulated at the top edge of the second reinforcing member and extending forwardly and resting on the side walls, 55

and a locking flap articulated to the front edge of the cover member and extending downwardly and engaging the inner side of the front wall, and a tab on the cover overlying the front wall.

- 5 11. In a carton formed from a single sheet of material, a front wall, side walls articulated at each end of the front wall, inner side walls articulated at the tops of the side walls and extending downwardly, side wall brace members articulated at the lower edges of the inner side walls and extending inwardly and provided with catch members, an inner front wall articulated at the top of the front wall and extending downwardly between the front ends of the inner side walls, a front wall brace member articulated at the bottom of the inner front wall and extending inwardly overlying the side wall brace members and held by the catch members, reinforcing members articulated at the bottom edges of the side members extending upwardly between the inner and outer side wall members, connecting members articulated to the rear ends of the side walls and extending inwardly and interlocking with each other, a bottom member articulated at the bottom edge of the front wall and extending rearwardly to the rear ends of the side walls and in contact with the side wall brace members, reinforcing members articulated at the sides of the bottom member extending upwardly between the inner side wall members and the reinforcing members of the side wall members, a rear wall articulated at the rear edge of the bottom member and extending upwardly, reinforcing members articulated at the sides of the rear wall and extending inwardly in contact with the rear wall and substantially in contact with the rear side of the connecting members, a first reinforcing member articulated at the top edge of the rear wall and extending downwardly substantially in contact with the front side of the connecting members, a second reinforcing member articulated at the bottom edge of the first reinforcing member and extending upwardly substantially in contact therewith, both the last-mentioned reinforcing members having ends inclined upwardly and lying back of the rear ends of the inner side walls, a cover member articulated at the top edge of the second reinforcing member and extending forwardly, and a locking flap articulated to the front edge of the cover member and extending downwardly and engaging the inner side of the front wall, and a tab on the locking flap extending upwardly through the cover.

ROBERT VAN ROSEN.
